Fig. 12

FIG. 1 is a perspective view of a plastic artificial fishing lure design of the present invention shown in its initially formed configuration;

FIG. 2 is a plan view of the lure of FIG. 1;

FIG. 3 is a front elevation of the lure of FIG. 1;

FIG. 4 is a perspective view of the lure of FIG. 1 shown in a representative configuration as it is drawn through water;

FIG. 5 is a plan view of the lure of FIG. 4;

FIG. 6 is a front elevation of the lure of FIG. 4;

FIG. 7 is a perspective view of a variation of the plastic artificial fishing lure design of FIG. 1;

FIG. 8 is a plan view of the lure of FIG. 7;

FIG. 9 is a front elevation of the lure of FIG. 7;

FIG. 10 is a perspective view of the lure of FIG. 7 shown in a representative configuration as it is drawn through water;

FIG. 11 is a plan view of the lure of FIG. 10; and
FIG. 12 is a front elevation of the lure of FIG. 10.

I claim:

The ornamental design for a plastic artificial fishing lure, as shown and described.
